UNITED STATES PATENT OFFICE.

AXEL A. STROM, OF AUSTIN, ASSIGNOR TO THE STROM MANUFACTURING COMPANY, OF CHICAGO, ILLINOIS.

SWITCH-STAND.

SPECIFICATION forming part of Letters Patent No. 398,354, dated February 19, 1889.

Application filed November 26, 1888. Serial No. 291,875. (No model.)

To all whom it may concern:

Be it known that I, AXEL A. STROM, a citizen of the United States, residing at Austin, in the county of Cook and State of Illinois, have invented a new and useful Improvement in Switch-Stands, of which the following is a specification.

My invention relates to an improvement in the class of so-called "automatic switch-stands," in which the switch-spindle may, on releasing the operating-lever from a peripheral recess in the revoluble table, be readily rotated, but wherein, when the operating-lever is in its normal hanging position in a peripheral slot of the table, the spindle, table, and a clutch are interlocked and so held by the yielding force of a stiff distended spring, requiring a force like that from the flange of a passing locomotive acting against the movable rail of a split switch to turn the spindle, and with it the table, thereby turning the movable part of the clutch on the immovable part against the resistance of the spring.

The object of my invention is materially to simplify the construction and operation of the species of switch-stand referred to, thereby considerably reducing the cost of manufacture, and at the same time to afford a generally-improved construction of the device.

In the accompanying drawings, Figure 1 is a vertical partly-broken section of a switch-stand of my improved construction. Fig. 2 is a plan view of the revoluble table, showing the relative positions of the radial peripheral slots. Fig. 3 is a broken sectional view of the upper part of the device, the section being taken at an angle on a horizontal plane to that shown in Fig. 1. Fig. 4 shows the two parts of the clutch in engagement; and Fig. 5 represents the crank of the vertical spindle shown in section, and which is normally off a dead-center with relation to the line of the switch-connecting bar. (Not shown.)

A is the hollow standard, inside of which, preferably near its lower end, is a web, r , supporting an internally-rectangular socket, q .

B is the table, having a central opening, around which is a sleeve, B', which enters the standard A when the table is adjusted in its position of resting on the upper end of the hollow standard, as shown, and the table,

which is circular, contains radial peripheral slots p . (Shown to be four in number and ninety degrees apart.)

C is a clutch, formed in two parts, each having a number of similar teeth, the lower part, n , being preferably annular and having a narrower rectangular hollow shank, n' , to fit in the rectangular socket q , whereby it is rendered stationary, and the upper part, m , having a rectangular shank, m' , of the same diameter through diagonally-opposite corners as the part m , which, like the part n , may be annular, the shank m' fitting into the lower end of the sleeve C, which should be rectangular internally to receive it. When the teeth of the part m mesh, as they ordinarily do, with those of the part n , the shank m' extends for some distance out of the sleeve.

D is the spindle, provided on its lower end with a crank, D', the spindle extending through the opening in the clutch C and out at its upper end through the top of the standard, where it carries a signal, E, and the crank is normally off a dead-center.

F is a yoke surrounding the spindle, to which it is keyed, and having a flange, l , at which it rests on the table B, the yoke being hollow, and by preference substantially so, above and below the flange, the lower part extending some distance into the circular opening in the table, which it fits, and thereby affording a bearing for the yoke inside the table as well as upon the upper surface thereof.

One side of the yoke, above the part which enters the table, is provided with a housing, F', closed at its top, thereby forming a firm connection with the main body of the yoke and rendering the latter strong throughout, and having an opening, i , in its flaring base to admit the operating-lever I, which is pivotally connected with the housing, as shown. The side of the housing is also provided with an opening, i' , to admit through it the staple or eye k on the operating-lever, with which the ordinary padlock (not shown) on the end of a chain engages to lock the lever against removal from a recess in the table.

G is a stiff spiral spring resting on the shank m' of the upper part of the clutch and surrounding the spindle inside the sleeve B',

the spring being confined between the clutch and the yoke F through the medium of a short sleeve, H; forming a continuation of the yoke, and which may or may not be integral therewith.

5 The operating-lever I normally hangs at an angle at which it may enter a recess, p, in the table B. To turn the spindle for setting a switch by hand, the lever I is raised out of a recess, p, and through its medium and the connection of the yoke with the spindle the latter may be turned without resistance from the clutch or spring, and when so turned the lever is allowed to fall into a recess, p. When 10 the switch is moved by a wheel of a passing train, the spindle is turned from the crank D', thereby turning also the table B, and, through the sleeve B' thereof, the upper part, m, of the clutch, and causing the latter to rise 15 against the spring G, compressing it, which, when the teeth of the upper part of the clutch have cleared the ends of those of the lower part, forces by its resilience the former into mesh with the latter.

15 25 What I claim as new, and desire to secure by Letters Patent, is—

1. In a switch-stand, the combination of a standard, A, supporting the lower stationary part, n, of a clutch, C, a recessed annular table, B, having a sleeve, B', extending into the standard, the upper part, m, of the clutch 30 extending into the lower end of the sleeve B' and longitudinally but not axially movable therein, a spindle, D, extending through the standard and clutch, a crank, D', at the end of the spindle, a spring, G, surrounding the spindle in the sleeve B' and pressing on the clutch, a yoke, F, secured to the spindle and confining the spring at its upper end, and an 35 operating-lever, I; substantially as described.

2. In a switch-stand, the combination of a standard, A, supporting a rectangular socket, q, a clutch, C, having a lower part, n, provided with a rectangular shank, n', fitting into the 40 socket q, a recessed annular table, B, having a sleeve, B', extending into the standard and rectangular on its interior near the lower end, the upper part, m, of the clutch having a 45

rectangular shank, m', fitting into the lower end of the sleeve B' and longitudinally movable therein, a spindle, D, extending through the standard and clutch, a crank, D', at the lower end of the spindle, a yoke, F, secured to the spindle, a spring, G, confined in the sleeve B' between the clutch and yoke, and 50 an operating-lever, I, substantially as described.

3. In a switch-stand having an annular peripherally-recessed revoluble table normally interlocked with the spindle and a clutch having a stationary part, and a rotary part actuated against the resistance of a confined spring, G, by turning the interlocked spindle, a yoke, F, secured to the spindle and provided with a flange, l, and extending below the flange into the opening in the table, and a lever, I, pivotally connected with the yoke and normally extending into a peripheral recess in the table, substantially as described.

4. A switch-stand comprising, in combination, a standard, A, having in its base a web, r, rigidly supporting a rectangular socket, q, a clutch, C, having a lower part, n, provided with a rectangular shank, n', fitting into the 55 socket q, a recessed annular table, B, having a sleeve, B', extending into the standard and rectangular on its interior near the lower end, the upper part, m, of the clutch having a rectangular shank, m', fitting into the lower end 60 of the sleeve B' and longitudinally movable therein, a spindle, D, extending through the standard and clutch and having a crank, D', at its lower end, a yoke, F, secured to the spindle and provided with a flange, l, and extending below the flange into the opening in the table, a spring, G, surrounding the spindle in the sleeve B', a sleeve, H, in the sleeve B' 65 between the upper end of the spring and the yoke, and an operating-lever, I, substantially as described.

70 AXEL A. STROM.
